METHOD OF MAKING A COMPOSITE COMMUTATOR SEGMENT
AND WINDING ELEMENT OF A BAR WOUND ARMATURE

Original Filed June 28, 1927

UNITED STATES PATENT OFFICE

VINCENT G. APPLE, OF DAYTON, OHIO; HERBERT F. APPLE, EDWARD M. APPLE, AND GOURLEY DARROCH EXECUTORS OF SAID VINCENT G. APPLE, DECEASED

METHOD OF MAKING A COMPOSITE COMMUTATOR SEGMENT AND WINDING ELEMENT OF A BAR WOUND ARMATURE

Original application filed June 28, 1927, Serial No. 202,139. Divided and this application filed March 24, 1930. Serial No. 438,515.

This invention is a division of my copending application Serial Number 202,139, filed June 28th, 1927, and relates to improvements in that type of armature which comprises a core, a bar winding and a commutator, and the objects of my improvements are, first, to provide a structure wherein the commutator is an integral part of the winding; second, to provide details of construction whereby the stock from which the winding bars are made is used with minimum waste; and third, to produce an article that is more durable and dependable and of better appearance than when made by present methods.

Further objects will be apparent from the detailed description when reference is made to the drawings, wherein—

Fig. 1 shows how a length of bar stock may be notched and cut apart so that each part comprises a commutator lug and a conductor bar.

Fig. 2 is a cross section taken at 2—2 of Fig. 1.

Fig. 3 shows how the two parts shown in Fig. 1 are reassembled.

Fig. 4 is a cross section taken at 4—4 of Fig. 3.

Fig. 5 is a cross section taken at 5—5 of Fig. 3.

Fig. 6 is an end view of Fig. 7.

Fig. 7 shows how the notching shown in Fig. 1 may be eliminated by substituting spot welding.

Fig. 8 is a perspective view of one unit of my winding.

Fig. 9 is another way of assembling the parts shown in Fig. 8.

Fig. 10 shows an armature core having a common type of core slot particularly suited to my invention.

Fig. 11 shows two of my improved winding units assembled with a core composed of laminæ Fig. 10.

Fig. 12 shows one pair of straight ends brought together to complete the circuit.

Fig. 13 is a view, partly in section, of a completed armature, insulating material having been molded through and about the winding to hold it in place and to bind the segments together to compose a commutator.

Similar numerals refer to similar parts throughout the several views.

For clearness in the following description a conductor bar so located relative to the commutator lug as to occupy a position in the outer layer of the completed winding may be referred to as an outer conductor bar and a conductor bar so located as to occupy a position in the inner layer may be referred to as an inner conductor bar.

Fig. 1 shows how a length of commutator bar stock, preferably copper, may be divided into two parts by cutting in at one edge, near one end, crosswise of the bar and substantially half way through, then lengthwise of the bar to near the other end, then crosswise of the bar and out through the other edge, the one part comprising a commutator lug 22 and an inner conductor bar 23, the other part comprising a commutator lug 24 and an outer conductor bar 25.

In Fig. 2 I show a cross section through a length of bar stock suitable for making the parts shown in Fig. 1, and it will be seen that the sides of the bar are inclined toward each other, forming what is commonly called a wedge shaped cross section. Bar stock of this form is readily obtainable, as it is commercially produced in varying wedge angles for use in making commutators of the conventional type.

After the length of stock has been separated as shown in Fig. 1 the one part may be turned end for end and the two commutator lugs 22 and 24 placed side by side leaving the two conductor bars 23 and 25 extend parallel to each other, although not in the same plane, the cross section Fig. 4 showing how the lugs 22 and 24 thus form a composite outline suitable for a commutator segment and the cross section Fig. 5 showing the relative position of the conductor bars 23 and 25.

In Figs. 6 and 7 I show another length of bar stock which has been cut apart in the same manner as that shown in Fig. 1, but which has not been notched at the ends as at 20 and 20. After the one part has been turned end for end and laid alongside the other part, the two commutator lugs 26 and 27 are spot welded together, and the welding bits are allowed

to make deep depressions, as at 28, 28, etc. into which a commutator segment holding means consisting of molded insulating material may afterwards extend to bind the segments together into a commutator.

In Fig. 8 I show the two parts of a winding unit with commutator lugs 22 and 24 placed adjacent to each other and the inner conductor bar 23 displaced in one direction 10 and positioned to occupy the inner half of a core slot and the outer conductor bar 25 displaced in the other direction and positioned to occupy the outer half of another core slot. The conductor bars may be displaced equal 15 amounts from their commutator lugs or they may be displaced the one more than the other, so long as the total spread between a bar 23 and a bar 25 is sufficient to compose a turn of the winding which is usually about one pole 20 pitch.

The lugs 22 and 24 may be brazed, welded or otherwise joined together either before or after the conductor bars are spread apart, or I may depend on the means afterwards employed for binding the whole commutator together to hold the pairs of lugs in contact, one with another, to provide electrical connection therebetween. Fig. 9 shows how the bent portions 31 and 32 of the bars 23 and 25 30 may be crossed if desired to achieve a result slightly different but equally as effective as that shown in Fig. 8. For clearness in description I will hereinafter refer to two commutator lugs that have been assembled as in 35 Figs. 8 or 9 as a commutator segment.

The winding apertures or slots of armature cores vary considerably in contour and proportion, a form much employed being shown in Fig. 10 at 33, 33, etc. The sides 40 of these slots are radial, so obviously the sides of the intervening teeth 34, and 34 are also radial. A slot and a tooth as here shown are, circumferentially, about of equal thickness. Winding units made from wedge 45 shaped stock and formed as in Figs. 8 or 9 are particularly adaptable to slots of this type since a composite commutator segment, composed of a lug 22 and a lug 24, is substantially equal, circumferentially, to a slot 33 50 and a tooth 34 together, which fulfills a condition required in providing a commutator of substantially the same diameter as the outside diameter of the winding.

Fig. 11 shows an armature core 35 of the 55 type having the sides of the slots and the teeth radial, the slots and teeth being, circumferentially, of substantially equal thickness. Assembled in its slots are two of my improved winding units. One unit comprises a commutator lug 22 having an inner conductor bar 23 integrally extending, and a commutator lug 24 having an outer conductor bar 25 integrally extending.

The other winding unit comprises a commutator lug 22a having an inner conductor

bar 23a integrally extending, and a commutator lug 24a having an outer conductor bar 25a integrally extending. The lugs 22 and 24 in electrical contact together provide one commutator segment, and the lugs 22a and 24a in electrical contact together provide another commutator segment. A spacer 36 of insulating material may separate the two segments. I may further, as in common practice, line the core slots with sheet 75 insulating material, though such linings are not shown in the drawings. While for clearness only two of my winding units are shown entered in the core, it is obvious that an entire winding may be arranged in cylindrical 80 formation and simultaneously endwise entered into the slots of a core in similar manner.

The free ends of the conductor bars 23, 23a, 25 and 25a extend through and considerably beyond the core 35, Fig. 11, and in Fig. 12 I show how one pair of these free ends are bent as at 37 and 38 and thus brought together as at 39 to be joined to complete the circuit, the manner in which this single pair 90 is joined being typical of the entire winding. The joints may be maintained by brazing, welding, or otherwise, welding being an approved method, and a welded joint is shown at 40 Fig. 13, but while I have here shown and described a method of joining the free ends of my winding units by bending said ends to form pairs as in Fig. 12, it is obvious that the older method of joining these ends with separate end connectors of involute or 100 other form may be employed if so desired.

As the method of stacking a complete set of winding units in cylindrical formation, pressing them simultaneously into the slots of a core, bending them simultaneously to form pairs, and joining the pairs by welding to complete the circuit, or joining the free ends with separate end connectors, is already known to the art, no extensive description 105 thereof is herein contained.

After a sufficient number of winding units are assembled to provide conductor bars to fill all of the core slots, and commutator lugs sufficient to make the commutator, and after all of the free ends have been bent and joined like the single pair shown in Fig. 12, or joined by separate end connectors, and all have been welded as at 40, Fig. 13, or otherwise joined, the armature may be placed in a mold, and a fluid insulating material 110 poured or pumped into the mold, and hardened or allowed to harden by heat or otherwise to form a solid insulating mass as at 41, 41, etc. to bind the segments together to compose a commutator and to enclose and hold the entire winding in place.

Having described my invention, I claim—

The method of making a winding unit comprising a commutator segment and two conductor bars comprising a single turn.

of a two layer bar wound armature from a length of bar stock of wedge shaped cross section which consists of cutting in at one edge at a point as near one end as the length 5 of said segment, crosswise of the bar and substantially half way through, thence lengthwise of the bar to a point as near the other end as the length of the segment, thence outwardly through the other edge, thus separating the bar into two parts, turning one of the parts end for end and placing the segment portions alongside with the flat sides together and the thicker edges both extending in the same direction, passing an electric current 10 from one to the other of said segment portions until they soften, pressing them together thereby making deep depressions for a commutator binding means and welding them with the same pressure, then spreading 15 the conductor bars apart to parallel spaced apart positions.

In testimony whereof I affix my signature.
VINCENT G. APPLE.
